UNITED STATES PATENT OFFICE

JAMES M. FROWENFELD, OF NEW YORK, N. Y.

DESIGN FOR A PIPE RACK

Application filed October 18, 1932. Serial No. 45,397. Term of patent 3½ years.

To all whom it may concern:

Be it known that I, JAMES M. FROWENFELD, a citizen of the United States, residing in New York, county and State of New York, have invented a new, original, and ornamental Design for Pipe Racks, of which the following is a specification, reference being had to the accompanying drawing, forming part thereof:

Fig. 1 is a plan view of the design.

Fig. 2 is a perspective view of the article showing my new design.

I claim:

The ornamental design for a pipe rack as shown.

JAMES M. FROWENFELD.
